UNITED STATES PATENT OFFICE

ALBIN T. LINN, OF PORT ANGELES, WASHINGTON

PIN LOCK

Application filed January 23, 1928. Serial No. 248,634.

My invention relates to pin locks and more particularly to locks for shackle or clevis pins that are used in the assemblage of cable, lumbering or other blocks. The primary objects 5 of the invention are to provide a pin lock whereby the pins that connect the several parts of a block may be positively held in place and thus prevent the falling of overhead loads and the consequent damage to life and 10 property. Other objects are to provide a pin lock that is simple, inexpensive and durable, that is self contained within the block, which is shielded against damage, and which may be readily unlocked when desired.

15 With the above and other objects in view which will appear as the description proceeds, the invention consists of the novel construction, adaptation, combination and arrangement of parts hereinafter described and 20 claimed. These objects are accomplished by devices illustrated in the accompanying drawings, wherein:

Figure 1 is a view in side elevation of a lumbering block and showing the lock applied 25 to one of the shackle pins;

Fig. 2 is a view in vertical section taken substantially on a broken line 2, 2 of Fig. 1;

Fig. 3 is a view in elevation showing a slightly different arrangement;

30 Fig. 4 is a view in horizontal section taken on a broken line 4, 4 of Fig. 3;

Fig. 5 is a view in side elevation of a shackle showing the device as adapted to lock the pin and nut together;

35 Fig. 6 is a view in front elevation of the same; and

Fig. 7 is a view in horizontal section taken on a broken line 7, 7 of Fig. 6.

Referring to the drawings throughout 40 which like reference numeral designate like parts, the numeral 5 indicates a cable block which may be a lumbering, halyard, or any other kind of block wherein pins are used for connecting the shackles, clevises or 45 other parts with the frame or shell of the block. Said block is provided with the usual upstanding lugs or eyes 6 and 7 and a shackle or clevis 8 is connected therewith by pins 9 passing through said lugs and the eyes 10 of 50 said shackle.

A cross plate 11 is usually interposed between the lugs 6 and 7 and eyes 10 and is provided with holes to correspond with the holes in said lugs and eyes for passage of the pins 9. Two of such plates are sometimes used as 55 clearly shown in Fig. 4 of the drawings. The smaller ends of the pins are burred or enlarged as at 12 and the holes 13 through the lugs 6 are made sufficiently large for passage of said enlarged ends, while the holes 14 60 through the lugs 7 are restricted to only permit the passage of the body portion of said pins. The enlarged ends of said pins cannot pass through said holes and it will thus be seen that said pins are prevented from becoming 65 separated from the device. It will be understood that the holes through the plates 11 are made to correspond with their associated holes through the lugs.

Referring to Figs. 1 and 2, I have provided 70 a casing 15 as an integral part of the block adjacent one of the lugs 6. A key member 16 having a head 17 at one end and a hook portion 18 at its other end passes through a hole in the upper wall of said casing. A helical 75 spring 19 disposed around the body portion of said key member and interposed between said upper wall of the casing and the head of the key member is expandingly adapted to retain said member in a normally locked position as shown in the drawings. In the locked position the extreme end portion of the hook 18 is disposed through a hole 20 in the pin 9.

To unlock the key member 16 it is merely 80 necessary to press upwardly on its head 17 85 sufficiently to raise the hook end 18 free of the hole 20 as will be readily understood. While I have only shown and described locking means for one of the pins 9 it will be understood that the same means may be used for the 90 other pin or pins if desired.

Referring to Figs. 3 and 4, the casing 15 is 95 made a part of one of the plates 11, otherwise the device is substantially the same as shown in Figs. 1 and 2. In Figs. 5, 6 and 7 a slot is cut in the nut 21 which together with the threaded hole in said nut forms the casing as will be readily understood. It is of primary importance that a casing be provided in all 100

adaptable forms of the device for the purpose of serving as a shield for the spring 19.

Having thus described my invention, it being understood that minor changes may be resorted to without departing from its scope and spirit, what I claim and desire to secure by Letters Patent of the United States is:

1. The combination with a cable block, of a pin lock comprising a hooked key member, a shackle, pins connecting said block and shackle, one of said pins having a hole therethrough, a spring for said key member adapted to normally retain the hooked portion of the key member within the hole in said pin, and a casing for the spring and key.
2. The combination with a cable block, of a pin lock comprising a hooked key member, a shackle, shackle pins connecting said block and shackle, one of said pins having a hole therethrough, a spring adapted to resiliently hold the hooked portion of said key within the hole in said pin, a casing for the spring and key, and means for preventing said shackle pins from becoming entirely disengaged from the block.

In witness whereof, I hereunto subscribe my name this 10th day of January A. D. 1928.

ALBIN T. LINN.
